RADIATOR

Filed April 22, 1922

Fig. 3.

INVENTOR.
A. W. Edwards

Murphy
ATTORNEY

UNITED STATES PATENT OFFICE.

ARTHUR W. EDWARDS, OF SACRAMENTO, CALIFORNIA.

RADIATOR.

Application filed April 22, 1922. Serial No. 556,053.

To all whom it may concern:

Be it known that I, ARTHUR W. EDWARDS, a citizen of the United States, and a resident of Sacramento, county of Sacramento, 5 and State of California, have invented a new and useful Radiator, of which the following is a specification.

The present invention relates to improvements in heat radiators and its particular 10 object is to provide a convenient and economical means for radiating heat which causes practically all the heat units carried by the products of combustion of a gas or oil burner to be utilized before the latter are 15 carried off into a chimney or other ventilating device. A further object of the invention is to provide a radiator of the character described that does not allow any of the 20 products of combustion to enter the room to be heated, so that no gas fumes or objectionable odors invade the room and the moisture usually associated therewith is avoided.

With these objects in view I have shown 25 the preferred form of my invention in the accompanying drawing, in which Figure 1 shows a side elevation of my radiator; Figure 2 a vertical cross section through the same, and Figure 3 a horizontal cross section along line 3—3 of Figure 2. While I 30 have shown only the preferred form of my invention, I wish to have it understood that various changes or modifications may be made within the scope of the claims hereto attached without departing from the spirit 35 of the invention.

My radiator (1) is supported on a base 40 plate (2) resting on the legs (3) and perforated as shown at (4), and supporting a burner (6) to which fuel is admitted through the pipe (7) controlled by the valve (8). An outer shell (9) extends between the base plate and the top plate (11) and engages suitable flanges (12) and (13) of the same. The top plate is provided with two concentric inner flanges (14) and (16) extending 45 downwardly and having secured thereto two inner shells (17) and (18) which extend downwardly to within close proximity of the burner (6). To the bottom of the inner shell (17) is secured a conical deflecting plate (19), a flange (21) of which extends into the said shell. The latter is also provided with a concentric inner flange (22)

which engages the inner shell (18) and holds the same in proper alinement.

It will be seen from this description and from the drawing that none of the products of combustion can enter either of the inner shells directly but are deflected by the cone (19) into the annular passage (23) between the outer shell (9) and the nearest inner shell (17). Perforations (24) are provided in the upper end of the shell (17) allowing the fumes to pass through the same into the annular space (26) between the two inner shells (17) and (18). The latter shell again is provided with a plurality of perforations (27) near its bottom which allow the fumes to pass and to rise within the inner shell.

The pipe (28) leading to the chimney not shown communicates directly with the inner shell (18) and is provided with an inner pipe (29) rigidly secured thereto by means of brackets (31). The latter pipe is closed 70 at the bottom by a conical deflecting plate (32) which deflects all the fumes or products of combustion into the annular passage (33) between the two pipes.

It will be seen that in this construction 80 the hot fumes or products of combustion are brought by the lower deflecting plate (19) in immediate contact with the outer shell (9), which again is in immediate contact with the air of the room so that the fumes are in their most effective place at the time when they carry the largest number of heat units. After a portion of these heat units 85 has been absorbed by the outer shell (9) the fumes are not allowed to go to waste but are guided through the tortuous passage outlined in the foregoing description and indicated by the arrows, during which time another considerable portion of heat units 90 is absorbed by the radiator. When passing from the body portion of the radiator into the pipe (28) leading to the chimney, they 95 are again forced into immediate contact with the pipe by means of the deflecting plate (32) and the inner pipe (29) so that the heat carried at that time may be further absorbed and utilized for the heating 100 of the room. Thereafter the fumes are carried off into the chimney so that none of the fumes are allowed to enter the room.

A central vertical rod (36) descending

through the point of the cone (32) and extending through the point of the cone (19) is anchored in the base plate by means of the nut (37) and holds the parts of the radiator together.

I claim:

1. In a heat radiator of the character described, a base plate, an outer shell, a source of heat operatively associated therewith, an inner shell supported above the source of heat, and having a deflecting plate secured to its lower end adapted to deflect the products of combustion from the source of heat toward the outer shell, a chimney pipe communicating with the space between the shells and having an inner tube mounted therein with a deflecting bottom adapted to deflect the products of combustion toward the chimney pipe, and means

for securing the inner tube and the chimney pipe to the radiator comprising a rod extending through the deflecting members and the base plate, and having means at either end for holding the same against removal.

2. In a heat radiator of the character described, a base plate, a shell mounted thereon, a top plate supported on the shell, a chimney pipe resting on the top plate and having an inner tube mounted therein with a deflecting bottom adapted to deflect the products of combustion toward the chimney pipe, and means for vertically binding the various members comprising a rod extending through the deflecting bottom of the chimney tube and the base plate and having means at either end for holding the same against removal.

ARTHUR W. EDWARDS.
